LIGHTING FIXTURE

George F. Johnston, Hendersonville, N.C., assignor to
General Electric Company, a corporation of New York

Filed Sept. 28, 1959, Ser. No. 842,814

5 Claims. (Cl. 240—51.11)

My invention relates generally to lighting fixtures, and more particularly to fixtures for elongated light sources and including an elongated reflector surrounding the light source and supported at its ends from a pair of junction boxes. The fixture is supported through the junction boxes which provide enclosed wiring chambers for the current supply means to the lamp socket at each end.

An object of this invention is to provide an improved arrangement for universal angular aiming adjustment of the reflector relative to any fixed position of the junction boxes at the ends thereof. For a better understanding of the invention, reference may be had to the following description and to the drawing wherein:

Fig. 1 is a perspective view of a lighting fixture comprising my invention;

Fig. 2 is a longitudinal cross section of a junction box at one end of the fixture and associated reflector end members mounted for rotation relative to the junction box;

Fig. 3 is a transverse cross section through the junction box along the line 3—3 in Fig. 2; and

Fig. 4 is a section corresponding to the left side of Fig. 2 but showing the reflector end member and associated elements in a position rotated 90° from that shown in Fig. 2.

Referring to the drawing, and speaking generally, the fixture comprises an elongated concave reflector 1, a pair of reflector end members 2 secured to the ends of the reflector and each carrying a lamp socket 3 to receive the bases at the ends of the lamp 4, such as a conventional fluorescent lamp, and a pair of junction boxes 5 to which are attached the reflector end members 2.

As shown in Fig. 1, the reflector 1 is secured at each end, by suitable fasteners such as bolts and nuts 6, to the correspondingly curved inner face of a flange 7 on the reflector end member 2. Each socket 3 is attached to the wall of the associated reflector end member 2 by screws 8 (Fig. 2) which extend through apertures or slots 9 (Fig. 3) at opposite sides of a hole 10 in said wall through which extend the current supply conductors 11 from the socket.

In accordance with the invention, there is provided a clutch plate 12 (Fig. 2) which is retained loosely in an internal circumferential groove 13 adjacent each side of the cylindrical body portion of the junction box 5 so that the said plate 12 can rotate through a full 360° in its groove. When the assembly of junction box 5 and clutch plate 12 is placed against the face of the reflector end member 2, an eyelet flange 14 on the clutch plate is engaged and located by the inner periphery or diameter of a circular rib 15' on the face of the reflector end member.

In assembling the parts, the junction box 5 and clutch plate 12 are rotated relative to the reflector end member 2 to align a pair of tapped holes 15 (Fig. 4) in the clutch plate with a pair of corresponding clearance holes in the reflector end 2, and a pair of screws 16 are inserted

2

through the said clearance holes and threaded loosely into the tapped holes.

With the installation of the screws 16, the reflector ends 2 and the clutch plate 12 are a fixed assembly and can rotate together relative to the junction box 5 to any desired angular position. By tightening the pair of screws 16, the clutch plate 12 is drawn tightly against the side of its retaining groove 13 and the side face of the junction box 5 is pulled tightly against the face of the reflector end member 2 or, preferably, against an interposed fiber gasket 17 which is cemented to the face of the reflector end member and is located thereon by the outer diameter of the circular rib 15'. The clutch plate 12, junction box 5 and reflector end 2 are rigid members, and tightening of the screws 16 causes the clamping load to be essentially uniformly distributed over the circumferential face rim of the junction box, and sufficient frictional surface is provided to prevent any rotational movement under service conditions such as any conditions of wind load encountered in outdoor use.

As shown herein, the clutch plate 12 is disc-shaped and truncated on opposite sides to permit insertion through an access port 18 in the junction box 5 and into its retaining groove 13. The access port 18 also serves the purpose of a wiring access opening and it is sealed by a gasketed cover 19 and two screws 20.

Also, as shown herein, the junction box 5 has a groove 13 for a clutch plate 12 at each side thereof. This permits a reflector end member 2 to be secured to each side thereof with independent rotational or angular adjustments of each of the reflector ends. Thus, any number of fixtures may be assembled in tandem. In the case of an end fixture, or an independent single fixture as shown in Fig. 1, the open end of the junction box 5 is sealed 35 with a flat disc plate 21 attached to an associated clutch plate 12 with the two screws 8 the same as a reflector end member 2.

Each of the junction boxes 5 provides an enclosed wiring chamber, and the integral tapped conduit nipple 40 22 enables the fixture to be mounted onto lengths of conduit to support each end, as well as to convey electrical supply conductors to the sockets 3.

In accordance with standard practice, the reflector end member 2 is preferably provided with a cylindrical 45 flange or skirt 23 concentric with the holes 10 and surrounding the socket 3 and adapted to receive one end of a flexible cylindrical rubber boot (not shown) which encloses the socket 3 and the end of lamp 4 to provide a weathertight enclosure. The sockets 3 may be of the 50 conventional telescopic type for receiving the bases at the ends of the lamp 4 and conducting current thereto.

What I claim as new and desire to secure by Letters Patent of the United States is:

1. In a lighting fixture, the combination of a pair of 55 spaced apart junction boxes, a pair of reflector end members located at respective opposed sides of said junction boxes, a socket carried by each of said end members to support therebetween a tubular lamp, a reflector extending between and secured to said reflector end members to enclose a lamp in said sockets, said junction boxes each having an internal circumferential groove 60 adjacent said side thereof, a clutch plate member having its periphery retained loosely in the said circumferential groove in each junction box for rotation therein, and 65 means for retaining each reflector end member and its associated clutch member against relative rotation therebetween and for drawing toward each other said clutch plate and reflector end member to clamp therebetween a portion of the associated junction box whereby to retain the assembly of reflector, reflector end members and clutch plates in a desired angular position relative to the junction boxes.

2. In a lighting fixture, the combination of a pair of spaced apart junction boxes, a pair of reflector end members located at respective opposed sides of said junction boxes, a socket carried by each of said end members to support therebetween a tubular lamp, a reflector extending between and secured to said reflector end members to enclose a lamp in said sockets, said junction boxes each having an internal circumferential groove adjacent said side thereof, a clutch plate member having its periphery retained loosely in the said circumferential groove in each junction box for rotation therein, and screw members extending through openings in each reflector end member and into threaded engagement with tapped holes in the associated clutch for retaining each reflector end member and its associated clutch member against relative rotation therebetween and for drawing toward each other said clutch plate and reflector end member to clamp therebetween a portion of the associated junction box whereby to retain the assembly of reflector, reflector end members and clutch plates in a desired angular position relative to the junction boxes.

3. In a lighting fixture, a junction box having an internal circumferential groove adjacent one side thereof, a reflector end member at said one side of said junction box, a socket carried by said reflector end member, a clutch plate having its periphery retained loosely in said circumferential groove for rotation therein, and means for retaining said reflector end member and clutch plate against relative rotation therebetween and for drawing toward each other said reflector end member and clutch plate to clamp therebetween a portion of the junction box whereby to retain the assembly of reflector end member and clutch plate in a desired angular position relative to the junction box.

4. In a lighting fixture, a junction box having a pair of internal circumferential grooves adjacent opposite

sides thereof, a reflector end member at each one of said sides of the junction box, a socket carried by each one of said reflector end members, a pair of clutch plates each having its periphery retained loosely in one of said circumferential grooves for rotation therein, and means for retaining each said reflector end member and its associated clutch plate against relative rotation therebetween and for drawing toward each other said reflector end member and clutch plate to clamp therebetween a portion of the junction box whereby to retain the assembly of reflector end member and clutch plate in a desired angular position relative to the junction box.

5. In a lighting fixture, a junction box having an internal circumferential groove adjacent one side thereof, 15 a reflector end member at said one side of said junction box, a socket carried by said reflector end member, a clutch plate having its periphery retained loosely in said circumferential groove for rotation therein, and screw members extending through openings in said reflector end member and into threaded engagement with tapped holes in said clutch plate for retaining said reflector end member and clutch plate against relative rotation therebetween and for drawing toward each other said reflector end member and clutch plate to clamp therebetween a portion of the junction box whereby to retain the assembly of reflector end member and clutch plate in a desired angular position relative to the junction box.
